FIG. 1

FIG. 2

FIG. 3

FIG. 4

FIG. 5

FIGURE 1 is a side elevational view of a mug washing machine or similar article, embodying the present design;

FIGURE 2 is a fragmentary perspective view;

FIGURE 3 is a top fragmentary plan view;

FIGURE 4 is a fragmentary front elevational view; and

FIGURE 5 is a fragmentary rear elevational view.

The brushes are partially omitted in FIGURE 1 and completely omitted in FIGURES 2 through 5 for convenience of illustration.

The dominant features of my design reside in the portions shown in full lines.

I claim:
The ornamental design for a mug washing machine or similar article, substantially as shown and described.
